RECOIL AND RUNNING-OUT GEAR FOR ORDNANCE.

1,109,047.

Specification of Letters Patent.

Patented Sept. 1, 1914.

Application filed May 27, 1910. Serial No. 563,782.

To all whom it may concern:

Be it known that we, ARTHUR TREVOR DAWSON, knight, and GEORGE THOMAS BUCKHAM, both subjects of the King of Great Britain, residing at 32 Victoria street, Westminster, in the county of London, England, have invented certain new and useful Recoil and Running-Out Gear for Ordnance, of which the following is a specification.

10 This invention relates to recoil and running out gear of the kind in which the recoil gear comprises a brake cylinder and the running out gear comprises an air compressor and a compressed air reservoir into 15 which the liquid contained in the compressor is forced by the recoil of the gun, the reaction of the compressed air in the said reservoir, after recoil causing the liquid to be forced back again into the air compressor and in so doing to effect the running out of the gun.

Recoil and running out gear of the above stated kind has already been proposed in which the brake cylinder and the air compressor are arranged within, and secured to, the air reservoir which is connected with the gun, communication between the air compressor and the air reservoir being effected by means of a passage in the wall of the 30 air compressor; on recoil these parts all move together with the gun, the pistons of the brake cylinder and air compressor being stationary and connected with the forward end of the gun cradle which is specially 35 formed to receive and protect the entire recoil and running out gear.

According to our invention we arrange the brake cylinder, the air compressor and the air reservoir within the gun cradle as afore- 40 said so that they move together when the gun recoils, but instead of arranging the brake cylinder and the air compressor within the air reservoir, we arrange them in front of the said air reservoir, to the forward end of which they are connected in any convenient manner, whereby the diameter of the cradle can be reduced and its length increased.

Communication between the interior of 50 the air compressor and that of the air reser-

voir may be effected by a port at the forward end of the air compressor leading to a passage in the wall of the air compressor, which passage may be connected with a tube extending longitudinally into the air reservoir in a position to insure that the free end of the tube shall always be covered with the liquid in the reservoir at any angle of elevation of the gun, as is necessary in this kind of recoil and running out gear. Instead of employing the said tube, we may place in the air reservoir the well known floating piston and we may provide the same with suitable packing rings, the said piston separating the air from the liquid which latter is in the forward part of the reservoir and always in communication with the end of the aforesaid passage in the wall of the air compressor. As is usual with this kind of gear we also provide a pressure gage for indicating the degree of internal pressure and for this purpose we may form the piston rod of the air compressor with a longitudinal hole or bore extending from its forward end to a point in front of the piston, where it communicates with the interior of the air compressor by a lateral passage or opening. To the forward end of this piston rod the pressure gage is attached so as to communicate with the said longitudinal hole thereof. The pressure gage may be protected from injury by a front cap attached to the cradle and furnished with a shutter to enable the dial of the gage to be inspected when desired. In order to permit of the air reservoir being replenished with compressed air for maintaining the proper pressure therein as required in connection with this kind of recoil and running out gear, we may provide the rear end of the air reservoir where it is attached to the lug on the gun, with a two-stage or other convenient form of air pump, the plunger of which may be suitably formed at its outer end to receive a handle for actuating it. This pump advantageously forms a component part of the air reservoir. The brake cylinder and its piston may be of any of the well known types suitable for the purpose.

In order that our said invention may be 100

clearly understood and readily carried into effect, we will describe the same more fully with reference to the accompanying drawings in which:—

5 Figure 1 is a sectional elevation showing a gun provided with our improved recoil and running out gear. Fig. 2 is a transverse section on the line 1—1 of Fig. 1. Fig. 3 is a transverse section on the line 2—2 of Fig. 1, and Fig. 4 is a sectional elevation showing an alternative construction.

A is the gun, B is the cradle on which it slides, C is the air reservoir, D is the brake cylinder with its piston D' and piston rod D², and E is the air compressor with its piston E' and piston rod E². The brake cylinder D is connected with the air reservoir by means of an externally screw threaded coupling piece D^x which screws into threaded 15 sockets in the rear end of the brake cylinder and in the forward end of the air reservoir; the air compressor E is made integral with the forward end of the air reservoir C. The rear end of said air reservoir passes 20 through a lug A' on the gun, and is retained in position by means of a nut A^x which screws on the end of the reservoir and bears against the rear face of said lug A', a key a^x being provided to prevent the said air 25 reservoir from turning. At the forward end of the air compressor is the port e leading to the passage e' in the wall of the said air compressor. This passage communicates with the tube E^x which extends into the air 30 reservoir C and which as aforesaid is of such a length and in such a position that the free end thereof is always covered with the liquid in the reservoir at any angle of elevation of the gun.

35 40 F is the pressure gage for indicating the degree of internal pressure said gage communicating with the interior of the air compressor through the longitudinal hole or bore e² in the piston rod E² and a lateral opening e^x. The pressure gage F is attached to the piston rod by means of a 45 screwed connection f.

45 F^x is the front cap which is attached to the cradle B and incloses the pressure gage; 50 it is as above stated furnished with a side shutter (not shown) to expose the dial of the gage when required.

G is the two-stage air pump which is 55 screwed into the rear end of the air reservoir. The plunger g of the said air pump is formed at its outer end as a ring g^x to receive a handle for actuating the said plunger.

60 In the modified construction shown in Fig. 60 4, H is the floating piston which is provided with packing rings h and which serves to separate the air in the rear end of the reservoir C from the liquid which is retained in the forward part of said reservoir, so that

the liquid is always in communication with 65 the aforesaid passage e'. The said piston H moves in the air reservoir C in accordance with the movement of the gun during recoil and thereby compresses the air in the reservoir C on the rear side of said piston. The 70 compressed air then reacts upon the liquid through the intervention of the piston and causes the gun to return to the run out position in the usual manner. The air compressor E instead of being integral with the 75 air reservoir C is screwed into the said reservoir to allow for the insertion and removal of the piston H when desired.

What we claim and desire to secure by Letters Patent of the United States is:— 80

1. In recoil and running out gear for ordnance the combination of a brake cylinder, an air compressor, an air reservoir, means for connecting the rear ends of the said brake cylinder and the air compressor to the 85 forward end of the air reservoir, and a floating piston in the air reservoir.

2. In recoil and running out gear for ordnance, the combination of a brake cylinder, an air reservoir, an air compressor having a 90 passage communicating with the air reservoir, means for connecting the rear ends of the said brake cylinder and the air compressor to the forward end of the air reservoir so that the 95 said cylinder and compressor project wholly in front of the reservoir, and a floating piston in the air reservoir.

3. In recoil and running out gear for ordnance, the combination of a brake cylinder, an air compressor arranged beneath said 100 brake cylinder, an air reservoir, means for connecting the rear ends of the said brake cylinder and the air compressor to the forward end of the air reservoir so that the 105 said cylinder and compressor project wholly in front of the reservoir, and a floating piston in the air reservoir.

4. In recoil and running out gear for ordnance, the combination of a brake cylinder, an air reservoir, an air compressor having a 110 passage communicating with the air reservoir, means for connecting the said brake cylinder and the air compressor to the forward end of the air reservoir and a floating piston in the air reservoir. 115

5. In recoil and running out gear for ordnance, the combination of a brake cylinder, an air reservoir, an air compressor having a 120 passage communicating with the air reservoir, means for connecting the said brake cylinder and the air compressor to the forward end of the air reservoir, a floating piston in the air reservoir and packing rings 125 on said floating piston.

6. In recoil and running out gear, the 12 combination of a brake cylinder, an air compressor, a piston rod of said compressor having a hole formed therein that terminates in

the air compressor, a pressure gage at the outer end of said hole, an air reservoir, and means for connecting the brake cylinder and the air compressor to the forward end of the

5 reservoir.

7. In recoil and running out gear, the combination of a brake cylinder, an air compressor, an air reservoir, means for connecting the said brake cylinder and the air compressor to the forward end of the air reser-

voir, and an air pump forming a component part of said air reservoir.

In testimony whereof we affix our signatures in presence of two witnesses.
